UNITED STATES PATENT OFFICE.

WILLIARD B. PRESTON, OF CHICAGO, ILLINOIS.

ELECTRIC MASSAGE-ROLLER.

SPECIFICATION forming part of Letters Patent No. 693,068, dated February 11, 1902.

Application filed December 4, 1901. Serial No. 84,656. (No model.)

To all whom it may concern:

Be it known that I, WILLIARD B. PRESTON, a resident of Chicago, in the county of Cook and State of Illinois, have invented certain new and useful Improvements in Electric Massage-Rollers; and I do hereby declare the following to be a full, clear, and exact description of the invention, such as will enable others skilled in the art to which it appertains to make and use the same.

My invention relates to an improvement in electric massage-rollers, the object of the invention being to provide a simple and inexpensive device of this character which will effectually perform all the desired functions of such an instrument.

With this object in view the invention consists in certain novel features of construction and combinations and arrangements of parts, as will be more fully hereinafter described, and pointed out in the claims.

In the accompanying drawings, Figure 1 is a view in elevation illustrating my improvements, and Fig. 2 is a view in section of the same.

1 represents a cylindrical block of hard rubber or other non-conducting material, made with parallel and longitudinal bores for the reception of metal shanks 2, integral with 30 metal brackets 4 and secured therein by lateral pins 3, as shown. The outer or free ends of the brackets 4 are made bifurcated, or, rather, in the form of parallel arms 4^a, between which are mounted to revolve on short 35 shafts 5 metal rollers 6. These shafts 5 project slightly inward beyond the brackets and into a bearing in a roller 7, of rubber or other non-conducting material, and while they serve to revolvably support the roller 7 they are 40 spaced apart and there is no electrical contact between them. The ends of shanks 2 project through the inner end of block 1 and are provided with screws 8 to secure the wires 9, connected up in circuit with a suitable battery, and a cylindrical handle 10, preferably of hard rubber or other non-conducting material, incloses the block 1, the inner ends of shanks 2, and a portion of the wires 9 and is

secured in position by a screw 11, passed through the handle 10 and into block 1. 50

The operation of my improvements is as follows: The operator grasps the handle 10 and runs the rollers 6 and 7 over the portion of the body to be treated. The rollers 6 form electrodes and the electric current is compelled to pass through the patient's body between rollers 6 to make the circuit, thus subjecting the unhealthy part to the current, and the non-conducting roller 7 serves to even the pressure on the body without interfering with 60 the proper circuit of the electric current.

Various slight changes might be resorted to in the general form and arrangement of the several parts described without departing from the spirit and scope of my invention, 65 and hence I would have it understood that I do not wish to limit myself to the precise construction set forth, but consider myself at liberty to make such slight changes and alterations as fairly fall within the spirit and scope 70 of my invention.

Having fully described my invention, what I claim as new, and desire to secure by Letters Patent, is—

1. In a massage-roller, the combination with 75 two brackets of electricity-conducting material spaced apart, of shafts in said brackets projecting inward beyond the same and spaced apart, rollers of conducting material on said shafts in the brackets, and a roller of 80 non-conducting material between the brackets and supported on the ends of the respective shafts.

2. In a massage-roller, the combination with a block of non-conducting material, metal 85 brackets, shanks on the brackets supported in the block and spaced apart, electric wires connected with the respective shanks, metal rollers carried by the brackets, a roller of non-conducting material between the brackets, 90 and a handle of non-conducting material surrounding the block.

3. In a massage-roller, the combination with a block of non-conducting material, metal brackets having shanks secured in parallel 95 bores of the block and spaced apart, screws

in the ends of said shanks for the attachment of electricity-conducting wires, metal rollers mounted to revolve in said brackets, a roller of non-conducting material mounted to revolve between the brackets, and a cylindrical handle inclosing the block, screws and a portion of the wires and removably secured to the block.

In testimony whereof I have signed this specification in the presence of two subscribing witnesses.

WILLIARD B. PRESTON.

Witnesses:

MARK R. SHERMAN,
JOSEPH B. BURTT.
